UNITED STATES PATENT OFFICE.

GEORGE B. DETERMANN, OF LOUISVILLE, KENTUCKY, ASSIGNOR OF ONE-HALF TO
J. F. WAGNER'S SONS CO., OF LOUISVILLE, KENTUCKY, A FIRM.

VENTILATOR.

1,183,804.

Specification of Letters Patent.

Patented May 16, 1916.

Application filed April 2, 1915. Serial No. 18,666.

To all whom it may concern:

Be it known that I, GEORGE B. DETERMANN, a citizen of the United States, residing in the city of Louisville, county of Jefferson, and State of Kentucky, have invented a new and useful Improvement in Ventilators, of which the following is a specification.

This invention relates to ventilators of the class comprising a vertical shaft and has for an object the provision of a damper which will not only control the flow of air from the interior, but which will effectively prevent the entrance of rain or snow which may be blown against the outside thereof.

Another object is the provision of a ventilator having an annular damper disposed on the exterior of the shaft with operating means therefor positioned within the shaft.

20 A further object is the provision of positive means for opening as well as closing the damper.

A still further object is the provision of simple effective means for maintaining the damper in a closed position.

With the foregoing and other objects in view the invention consists of the novel construction and arrangement of parts illustrated in the accompanying drawings which 30 form a part of this specification, wherein is set forth an embodiment of the invention, but it is to be understood that such changes and modifications may be resorted to as come within the scope of the appended 35 claim.

Referring to the drawing wherein similar reference characters designate like parts in the several views: Figure 1, is a perspective view, with parts broken away, showing the 40 damper in open position. Fig. 2, a vertical section, showing the damper closed. Fig. 3, a plan of a ventilator having a glass top for the admission of light. Fig. 4, a section on line 3—3 of Fig. 3, showing the damper 45 open. Fig. 5, a detached detail, on an enlarged scale, of the means for securing the glass top on the ventilator shaft. Fig. 6, a detached detail, on an enlarged scale, of the operating levers as holding the damper elevated (in closed position).

The ventilator is adapted to be placed above an opening in the roof of a building, or otherwise, in the usual manner and comprises a main shaft —10— preferably cylindrical, formed of any suitable material, a

hood, or top, —12—, preferably cone shaped, is supported above the shaft a suitable distance by means of vertical arms —13— which are secured respectively to the inner side of the shaft and the under surface of the top. 60 The top which is of greater diameter than the shaft prevents rain, snow or down drafts of air from entering same. A weather band —14—, positioned about the ventilator, to prevent the entrance thereinto of side currents of air, extends from a point above the edge of the hood to a point below the upper end of the shaft, and is supported by braces —15— which extend from the hood. A sleeve, or damper —16— is disposed about 70 the upper end of the shaft and is adapted to slide thereon and be extended beyond the end thereof to contact with the hood and close the space therebetween. A transverse bar —17— which extends across the upper 75 end of the sliding damper and is secured at each end thereto, rests upon the upper end of the shaft and acts as a support for the damper. A transverse bar —18— which is secured within the shaft, a suitable distance 80 below the top thereof and parallel with the bar 17 serves as a support for a lever —19— which is pivotally connected intermediate its ends therewith by means of a bolt —20—. This lever has on one end an angular return 85 —21— which extends therefrom at an acute angle toward the pivotal point 20. A connecting rod —22— is pivotally connected by means of bolts —23— and —24— respectively to the free end of said return and to 90 the bar 17. Chains —25, and 26—, or their equivalents, secured to the ends of the levers 19, depend therefrom and are provided, on their lower ends, with tabs —27 and 28— indicating which to pull to obtain a desired 95 result. A pull on the tab 27, labeled "Shut" will elevate the lever 19, on which is the extension 21, and through the medium of the connecting rod 22, the sliding damper 6, moving it into the closed position. As the 100 damper reached the upper limit of its movement the pivotal point 23 passes beyond a line falling through the pivotal points 20 and 24 and the damper would descend by 105 gravity, pushing the lever 19 on around, but that a shoulder, or abutment —30—, on the arm 22, contacts with the extension 21, and further relative movement of the lever 19 and arm 22 is prevented. The damper remains elevated until traction is exerted on 110

the chain 26. It will be observed that with this construction the damper is securely held, or locked, in an elevated, or closed position, and can only be lowered, or opened, by traction on the chain 26. A ledge —31— is disposed about the damper to deflect moisture therefrom. In some cases it may be desired to provide a ventilator with a glass top, for the purpose of admitting light in such cases the center portion of the hood 12 is cut away leaving a frustum shaped rim —32— which is supported by the arms 13. An annular band —33— having an outwardly extended horizontal flange —34— is supported, or held in position, by vertical extensions —35— from the braces 15. A glass top —36— rests on the flange 34 and is encircled by a flanged rim —37— which in turn is held in place by means of clips —38— secured on horizontal returns —39— from the vertical member 35 by means of bolts —40. It will be seen that by this construction a strong and inexpensive ventilator is provided. The damper being located outside the main shaft will positively prevent water or snow, which may be blown against the damper when closed, getting inside the main shaft. The method of operating this damper is very rapid, and positive; only a short pull on one chain or the other being required to open or close the damper, and also secure same in such a position; thus permitting

chains to depend within reaching distance, or to be extended to a convenient point. By the use of two chains, one to open and one to close, the operations are equally rapid and positive. The possibility of not being able to operate the damper one way or the other, due to such common causes as thick paint, cinders, dirt between the damper and shaft, etc., is reduced to a minimum, as dependence is not placed upon the damper dropping by gravity.

Having thus described my invention so that anyone skilled in the art pertaining thereto, may make and use the same, I claim:

A fixed support, a lever of the first order pivoted thereon, manipulative means depending from each end of said lever, an angular return on one end of said return and to an object to be raised, the point of attachment of said object and the pivot of said lever being in a vertical line, an abutment on said arm adapted to contact with the return after the pivotal point, between the arm and the return, has passed said vertical line, whereby the further movement of the arm and lever is stayed and the object sustained in the raised position.

GEORGE B. DETERMANN.
